WARP KNITTING MACHINE

Fritz Lambach, Tenafly, N. J.

Application September 20, 1945, Serial No. 617,537

22 Claims. (Cl. 66—84)

1

My invention relates to textile machines, and more particularly to warp knitting machines, wherein reciprocable sinkers are arranged for holding down the fabric when the needles are moved upwardly. If such warp knitting machines are equipped with one or more reciprocable filler thread carriers for laying filler thread substantially parallel to the series of needles, such reciprocable sinkers act also as so-called filler sinkers for placing the filler thread laid by said filler thread carrier or carriers into position to be incorporated into the fabric produced by the knitting implements of the machine.

An object of my invention is to improve on the construction, arrangement and shape of such sinkers in said types of warp knitting machines.

In the hitherto customary warp knitting machines of above described types there are many factors having an unfavorable influence on the construction, arrangement and shape of the sinkers. For example, it is customary to provide the sinkers at their ends with tine like projections arranged for receiving the filler thread laid by the filler thread carrier, as shown for example in the U. S. Patent 2,200,280 to Klumpp and Lambach. It has been found in practice, that said tine like projections are often the cause of disturbances. When, during the knitting operations, the reciprocable filler sinkers are moved forwardly toward the needles, one or the other of said tine like projections arranged for entering into the extremely small space between the needles may accidentally hit such a needle and cause a bending thereof, inasmuch as the hitherto known machines are not equipped with means capable of guiding the free ends of the filler sinkers. Moreover, said tine like projections of the filler sinkers may easily cause an undesired displacement of the warp yarns running from the warp guides of the machine to the needles, when the filler sinkers are moved toward the needles.

Furthermore, in the hitherto known warp knitting machines of above described types the customary arrangement of a stationary latch retaining wire cooperating with the latches of latch needles has an unfavorable influence on the shape of the active end portion of the sinkers, as care has to be taken, that the sinkers do not come into engagement with said latch retaining wire during their forward movement. On the other hand, such a stationary latch retaining wire is subject to undesired vibrations

2

caused by the warp yarns, when the latter hit said wire during a backward movement of the oscillating warp guides. Moreover, the warp yarns, abutting against the wire are bent at the point of engagement with the wire with the result of a change in the tension of the warp yarns.

It is an object of my invention to provide a warp knitting machine of above described type with means eliminating the disadvantages enumerated above.

It is a further object of my invention to provide a warp knitting machine of above described type with means guiding the free ends of the sinkers.

15 It is still another object of my invention to provide a warp knitting machine of above described type with means shielding the free ends of the filler sinkers when the latter are in their extreme backward position so as to prevent an undesired engagement between the filler sinkers and the filler thread carrier or carriers when the latter are moved for laying filler thread.

It is a further object of my invention to provide a warp knitting machine of above described type, wherein the sinkers and the latch retaining wire are in close proximity to each other when the sinkers are in their extreme forward position.

With the above and other objects of the invention in view, the invention consists in the novel construction, arrangement and combination of various devices, elements and parts, as set forth in the claims hereof, certain embodiments of the same being described in the specification and being illustrated in the accompanying drawings forming part of this specification, wherein:

Fig. 1 is a front elevational view of a warp knitting machine according to the invention, some parts being broken away and some parts being shown in section,

Fig. 2 is a vertical sectional view of the warp knitting machine, taken on line 2—2 of Fig. 1,

Fig. 3 is a sectional view similar to the sectional view shown in Fig. 2, said Fig. 3, however, illustrating only the knitting implements and their actuating drives in an enlarged scale,

Fig. 4 is a vertical sectional view of the machine taken on line 4—4 of Fig. 1, said Fig. 4 illustrating the latch retainer drive,

Fig. 5 is a fragmentary right-hand side elevational view of the warp knitting machine, illustrating the carrier drive actuating the reciprocable filler thread carrier,

55 Fig. 6 is a top plan view of a set of guiding

elements extending between a stationary part of the machine and the trick plate and cooperating with the reciprocable filler sinkers,

Fig. 7 is a vertical sectional view of a portion of the machine taken on line 7-7 of Fig. 6.

Figs. 8-13 are somewhat diagrammatical illustrations of various positions of the latch needles, the filler sinkers, the guides, and the latch retaining wire relative to each other during a knitting operation.

Referring now to Figs. 1 and 2, 20 generally indicates the frame of the warp knitting machine composed of several parts in any suitable manner: A main cam shaft 22 journaled in suitable bearings of the frame may be rotated by a motor 24 connected with said main cam shaft through a belt drive generally indicated by 26.

Several sinker bar cams 28 (only one being shown in the drawings) are keyed to the main cam shaft 22. Each of said sinker bar cams 28 is in operative engagement with a roller 30 (see Figs. 1, 2 and 3) rotatably mounted on a sinker bar rocker 32 keyed to a sinker bar shaft 34 rotatably mounted in suitable bearings of the frame. A tension spring 36 stretched between one end of said sinker bar rocker 32 and a stationary point 38 of the machine tends to urge the roller 30 against the surface of the sinker bar cam 28. The other end of said sinker bar rocker 32 and the free end of a plurality of sinker bar arms 40 keyed to the sinker bar shaft 34 carry a sinker bar 42 secured to said ends of the sinker bar rocker and sinker bar arms by screws. The sinker bar 42 extending over the width of the warp knitting machine carries a series of filler sinkers 44 secured thereto in any suitable manner. Above described sinker bar drive 28, 30, 32, 34, 40, associated with said sinker bar 42, may reciprocate the sinker bar 42 with its filler sinkers 44 in a forward and backward direction in dependence on the shape of the sinker bar cam 28.

Furthermore, several needle bar cams 46 are keyed to the main cam shaft 22. Each of said needle bar cams cooperates with a roller 48 journaled on a needle bar rocker 50 swingably mounted on the sinker bar shaft 34. A tension spring 52 stretched between the needle bar rocker 50 and the stationary point 38 of the machine tends to urge the roller 48 against the surface of the needle bar cam 46. On each side of the needle bar rocker 50, one end of a connecting link 54 is pivoted to the needle bar rocker 50 at 56. The other end of said connecting link 54 is pivotally and adjustably connected with a needle bar arm 58 keyed to a needle bar shaft 60 rotatably mounted in suitable bearings of the frame 20. A needle bar 62 carrying a series of latch needles 64 and extending over the width of the machine is secured to the needle bar arms 58 by screws. Each of the latch needles passes through a slot 66 of a trick plate 68 secured to a member 70 of the frame. Above described needle bar drive 46, 48, 50, 54, 58 associated with the needle bar 62 may reciprocate said needle bar 62 with its latch needles 64 in an upward and downward direction in dependence on the shape of the needle bar cam 46.

Furthermore, several guide bar cams 72 are keyed to the main cam shaft 22. Each of said guide bar cams cooperates with a roller 74 rotatably mounted on a guide bar rocker 76 swingably mounted on the sinker bar shaft 34. A tension spring 78 stretched between the guide bar rocker 76 and the stationary point 38 tends to urge the roller 74 against the surface of the

guide bar cam 72. One end of a connecting link 80 is pivotally and adjustably connected with the guide bar rocker 76 at 82, the other end of said connecting link 80 is pivoted to one end of a guide bar arm 84 at 86. The other end of said guide bar arm 84 is keyed to a guide bar shaft 88 rotatably mounted in suitable bearings of the frame 20. A plurality of guide bar hangers generally indicated by 90 is secured to said guide bar shaft 88. Said guide bar hangers 90 carry a plurality of guide bars 92 (in the embodiment shown in the drawings, the machine is equipped with five guide bars) extending over the width of the machine. Each of said guide bars 92 carries a series of warp guides 94, by means of which warp yarns 96 (see Fig. 2) drawn from rotatable warp beams 98 are fed to the latch needles 64. Above described guide bar drive 72, 74, 76, 80, 84, 90 associated with the guide bars 92 may reciprocate the guide bars 92 with their warp guides 94 in a forward and backward direction in dependence on the shape of the guide bar cam 72. Furthermore, the guide bars 92 with their warp guides 94 may be reciprocated in a longitudinal direction by means of a pattern chain drive (not shown in the drawings) in a manner known per se.

As best shown in Figs. 3, 6 and 7, several blocks 100 are secured to a stationary bar 102 extending over the width of the machine; said bar 102 forms a part of the frame 20. A series of spaced guiding elements 104, 106, 108 is inserted into a recess 110 of each block 100. The guiding elements 104, 106, 108 are secured to the block 100 by a pin 112 passing through registering holes in the wall of the block and in the guiding elements. Thus, the guiding elements 104, 106, 108 secured to the block 100, which in turn is secured to the bar 102 form stationary elements of the machine. Furthermore, the guiding elements 104, 106, 108 are connected with each other at their ends projecting from the block 100 by a pin 114 passing through registering holes of the guiding elements. The guiding elements 104 are of shorter length than the guiding elements 106, 108; furthermore, the main body of the guiding elements 104 is twice as thick as the main body of the guiding elements 106, 108. The guiding elements 106, 108 each have an offset projection 116, 118, respectively, in alignment and in loose engagement with a partition 120 of the trick plate 68 adjacent the slot 66 receiving the reciprocable latch needle 64. This arrangement of said projections 116 and 118 of the guiding elements 106 and 108 in alignment with the partitions 120 permits a free upward and downward movement of the latch needles 64 and swinging of the latches 122 about their pivot 124 on the latch needles 64 during the performance of knitting operations. The main body of the guiding elements 104, 106, 108 is arranged in such a way, that spaces 126 are formed, which are in line with the partitions 120 of the trick plate. Each of said spaces 126 is in turn arranged for receiving a filler sinker 44, so that the filler sinkers are guided by the guiding elements 104, 106, 108 during a forward and backward movement of the filler sinkers 44 by means of the sinker bar drive described above. Said guiding of the free ends of the filler sinkers 44 assures a proper entering thereof into the space between the latch needles 64, so that they cannot hit the latch needles 64, and cannot displace the warp yarns when they are moved forwardly into the extreme forward position shown in dash and dot lines in Fig. 7. Furthermore, as may be readily gathered

from Fig. 7 illustrating the two extreme positions of a filler sinker 44, a portion of each filler sinker is always in the space 126 (see Fig. 6) between adjacent guiding elements for being embraced by the latter, so that an undesired abutment of a filler sinker against a stationary guiding element during a movement of the filler sinkers from the extreme retracted position to the extreme advanced position is eliminated. Moreover, the upper edge of each of the spaced stationary guiding elements 104, 106, 108 is shaped in such a way, that it shields the free end of the adjacent filler sinker 44, when the latter is in its extreme backward position as shown in full lines in Fig. 7. As will be readily understood, the spaced stationary guiding elements 104, 106, 108 form a bridge extending over the width of the machine.

As best shown in Fig. 1, an endless band 128 of flexible material is trained around two drums 130, 132. Each of said drums is journaled in suitable bearings of brackets mounted on the frame. The drum 132 is connected with a drive, the so-called carrier drive, to be described hereinafter, by means of which the drum 132 may be alternatively rotated in clockwise direction and counter-clockwise direction, whereby a reciprocating movement is imparted to the band 128 at predetermined intervals. A filler thread carrier generally indicated by 134 is secured in any suitable manner to said flexible band 128. The drawings illustrate only one filler thread carrier, but it is understood that a plurality of filler thread carriers may be attached to the band 128, if desired. The filler thread carrier receives a filler thread 136 (see Fig. 3) from a filler thread supply (not shown). When the filler thread carrier 134 is moved by means of the band 128 from its extreme right-hand position into its extreme left-hand position and vice versa, filler thread is laid by said filler thread carrier 134 substantially parallel to the series of latch needles 64 onto the guiding elements 104, 106, 108 forming a bridge between the stationary member 102 and the trick plate 68 as described above. The reciprocating movement of the filler thread carrier 134 takes place when the filler sinkers 44 are in their extreme backward position as shown in Figs. 3 and 7. As mentioned above, the filler sinkers are shielded by the guiding elements 104, 106, 108, when they are in said extreme backward position, so that they are protected from an undesired accidental engagement of the moving filler thread carrier with their free end portion.

The carrier drive associated with the filler thread carrier 134 for reciprocating same is best shown in Figs. 1 and 5. A pinion 138 keyed to the end of the main cam shaft 22 is in mesh with a gear 140 keyed to a shaft 142 journaled in suitable bearings of the frame. A cam 144 keyed to said shaft 142 is in engagement with a roller 146 rotatably mounted on a rocker 148 keyed to a shaft 150 journaled in bearings of the frame. A tension spring 152 stretched between the rocker 148 and a stationary point 154 of the machine tends to urge the roller 146 against the surface of the cam 144. An arm 156 having a slot 158 is keyed to the shaft 150. A pivot 160 pivotally connecting the arm 156 with one end of a connecting link 162 may be adjusted in a desired position in said slot 158. The other end of said connecting link 162 is pivoted to an arm 164 at 70 166. Said arm 164 is keyed to a shaft 168 journaled in bearings of the frame. The end of an arm 170 keyed to said shaft 168 is pivoted to one end of a connecting rod 172 at 174. The other 75

end of said connecting rod 172 is pivoted to a rack 176 at 178. Said rack 176 is slidably arranged in a guide 180 mounted on a bracket 182 of the machine. A pinion 184 in mesh with said rack 176 is keyed to a shaft 186 journaled in bearings of the bracket 182. The drum 132 engaged with the band 128 carrying the filler thread carrier or carriers is keyed to the shaft 186. As will be readily understood, above described carrier drive 138, 140, 144, 148, 156, 162, 164, 170, 172, 176, 184, 132, 128 may cause a movement of the filler thread carrier to the right or to the left depending on the upward or downward movement of the rack 176 in dependence on the shape of the cam 144. The ratio between the pinion 138 and the gear 140 is 1:2, and the cam 144 is of such a shape, that the filler thread carrier performs either one movement to the right or one movement to the left at a predetermined interval during one full rotation of the main cam shaft 22, i. e. one cycle, of knitting operations. The length of the stroke of the filler thread carrier or carriers may be adjusted by an adjustment of the pivot 160 in a predetermined position relative to the 25 slot 158.

As best shown in Figures 1, 3 and 4, the machine is equipped with a latch retaining wire 188 extending over the width of the machine for co-operation with the latches of the latch needles at 30 a predetermined interval during a cycle of knitting operations. Said latch retaining wire is stretched between two bell crank levers 190 arranged on each side of the machine. Each bell crank lever 190 is pivoted to a stationary bracket 192 at 194. The arm 196 of each bell crank lever 190 is pivoted at 198 to one end of a connecting link generally indicated by 200. Said connecting link 200 comprises two members 202 and 204 connected with each other by a threaded bolt 206 35 engaged with threaded bores of said members 202 and 204. Said threaded bolt 206 permits an adjustment of the length of the connecting link 200. The other end of said connecting link 200 is pivoted at 208 to an arm 210 keyed to the sinker shaft 34. Thus, the latch retaining wire 188 stretched between the bell crank levers 190 is moved forwardly and backwardly by means of the above described latch retainer drive 210, 200, substantially simultaneously with the forward and backward movements of the filler sinkers 44 driven by the sinker bar drive including the sinker bar shaft 34. If desired, however, the latch retaining mechanism 190, 188 may also be driven by another drive associated with the main cam shaft.

Figs. 8-13 illustrate the cooperation of above described knitting implements controlled by the arrangement and shape of the various cams on the main cam shaft during one revolution of the main cam shaft, i. e. during one cycle of knitting operations.

The position of the knitting implements shown in Fig. 8 corresponds to the position of the knitting implements shown in Figs. 3 and 7, wherein the latch needles 64 are in their highest position, and the filler sinkers 44, the warp guides 94, and the latch retaining wire 188 are in their retracted extreme backward position. Filler thread 136p laid during a preceding movement of the filler thread carrier (not shown in Fig. 8) is at this interval of the knitting operation in front of the latch needles 64 for a subsequent incorporation into the fabric produced by the knitting implements of the machine. The main

cam shaft (not shown in Fig. 8) is in a position which is called hereinafter its starting position.

After a rotation of the main cam shaft through an angle of approximately 75° from above mentioned starting position, the knitting implements are in the position shown in Fig. 9. The latch needles 64, the filler sinkers 44, and the latch retaining wire 188 are still in the same position as in Fig. 8, the warp guides 94, however, are now in their extreme forward position, and in the meantime the filler thread carrier has been moved along the latch needles for laying fresh filler thread 136 onto the guiding elements 104, 106, 108.

After a rotation of the main cam shaft through an angle of approximately 195° from above mentioned starting position, the latch needles 64 are in their lowest position shown in Fig. 10 having formed loops from warp yarn fed by the warp guides 94 and having incorporated the filler thread 136p (shown in Figs. 8 and 9) into the fabric. The fabric and the filler thread 136p are not shown in Fig. 10. Now, the filler sinkers 44 and the latch retaining wire 188 start their forward movement.

During said forward movement of the filler sinkers 44, their notches 212 come into engagement with the filler thread 136 laid onto the guiding elements 104, 106, 108 for pushing same forwardly as illustrated by Fig. 11. Said Fig. 11 shows an intermediate position of the filler sinkers 44 and the latch retaining wire 188 during their substantially simultaneous forward movement, and the position of the knitting implements shown in said Fig. 11 is reached after a rotation of the main cam shaft through an angle of approximately 215° from above mentioned starting position.

After a rotation of the main cam shaft through an angle of approximately 225°, the filler sinkers 44 and the latch retaining wire 188 are in their extreme forward positions shown in Fig. 12. The filler sinkers now place the filler thread 136 in front of the latch needles 64 being in an intermediate position during their upward movement, so that the filler thread may consequently be incorporated into the fabric.

Fig. 13 illustrates the position of the knitting implements after a rotation of the main cam shaft through an angle of substantially 240° from above mentioned starting position. The latch needles 64 are now in a somewhat higher position but not yet in the highest position. The filler sinkers 44 being somewhat retracted are in such a position that, during a predetermined interval, the edge 214 thereof may hold down the fabric hanging on the latch needles when the latter are moved upwardly. Thus, the filler sinkers now act as a stitch comb holding down the fabric whereby the loops formed previously become disengaged from the latches 122 of the latch needles, which, at this time, are automatically opened. Such a disengagement of the loops from the open latches 122 takes place under a certain tension in the fabric, so that it may happen, that the latches swing automatically upward under the reaction of said tension. Such an automatic upward swinging of said latches 122 would cause an undesired closing of the latch needles which must be eliminated. As shown in Fig. 13, at this interval of the knitting operations, the latch retaining wire 188 being still in the same position as shown in Fig. 12, is in the path of the latch needles, so that if they should swing upwardly, they abut against the latch retaining wire 188 as soon as they reach the position 122' shown in

5 dash and dot lines. Thus, the latch retaining wire 188 prevents a closing of the latch needles, as the latches 122 will return into their proper open position by the action of their own weight after an engagement with the latch retaining wire.

After the performance of a full revolution, i. e. a rotation through 360° from the starting position, the knitting implements are again in the position shown in Fig. 8.

As will be readily understood from above, the substantially simultaneous movement of the filler sinkers 44 and the latch retaining wire 188 prevents an undesired abutment of the filler sinkers 44 against the latch retaining wire, when the filler sinkers are moved forwardly. As may be seen from Figs. 8-13, the angle of oscillation of the filler sinkers is larger than the angle of oscillation of the latch retaining wire 188. A fine adjustment of said ratio of the angles of oscillation may be obtained by the adjustable connecting link 200 shown in Fig. 4.

Furthermore, the movable arrangement of the latch retaining wire 188 permits the filler sinkers and the latch retaining wire to be in close proximity to each other when the filler sinkers are in their extreme forward position.

Furthermore, it will be obvious, that the warp yarns fed by the warp guides 94 to the latch needles 64 cannot come into engagement with the latch retaining wire 188, when the warp guides 94 are moved from their forward position shown in Fig. 13 into their rearward position shown in Fig. 8, as substantially at the same time the latch retaining wire 188 is also moved backwardly. Consequently, undesired vibrations of the latch retaining wire caused by an engagement of warp yarns with said wire are eliminated and likewise changes in the tension of the warp yarns caused by a bending of warp yarns over the latch retaining wire are prevented.

As best shown in Fig. 2, the fabric 216 produced by the knitting implements is taken up by a take-up roller 218 after passing over a series of tension rollers 220. The take-up roller 218 and the tension rollers 220 are driven in any suitable manner by the main drive of the machine.

I have described preferred embodiments of my invention, but it is understood that this disclosure is for the purpose of illustration and that 50 various omissions or changes in shape, proportion or arrangement in parts as well as the substitution of equivalent elements for those herein shown and described may be made without departing from the spirit and scope of the invention 55 as set forth in the appended claims.

For example, the warp knitting machine described above and shown in the drawings may be operated without the use of the filler thread carrier and its drive, or else, the sinker arrangement and the latch retaining mechanism according to the invention may be applied to warp knitting machines which have no filler thread carrier and filler thread carrier drive at all. In such a case, the sinkers perform only the action of a stitch comb for holding down the fabric when the needles are moved upwardly.

What I claim is:

1. A warp knitting machine comprising: a needle bar carrying a series of needles, a needle bar drive associated with said needle bar for imparting periodic reciprocating movements to same with its needles in a predetermined direction, at least one guide bar carrying a series of warp guides, a guide bar drive associated with said guide bar for periodic actuations thereof with its warp

guides so as to feed warp yarns to said needles, a sinker bar carrying a series of sinkers, a sinker bar drive associated with said sinker bar for imparting periodic movements to same with its sinkers toward and away from the direction of the strokes of said needles, said sinkers being arranged and shaped so as to form a stitch comb capable of holding down at predetermined intervals the fabric produced by the knitting implements of the machine, a stationary trick plate having apertures for the passage of said needles, and a series of spaced stationary guiding elements, said series of spaced stationary guiding elements being secured to a stationary part of the machine and extending between said stationary part and said stationary trick plate, and each of said sinkers extending into a space between said spaced stationary guiding elements.

2. A warp knitting machine comprising: a needle bar carrying a series of needles, a needle bar drive associated with said needle bar for imparting periodic reciprocating movements to same with its needles in a predetermined direction, at least one guide bar carrying a series of warp guides, a guide bar drive associated with said guide bar for periodic actuations thereof with its warp guides so as to feed warp yarns to said needles, a sinker bar carrying a series of sinkers, a sinker bar drive associated with said sinker bar for imparting periodic movements to same with its sinkers toward and away from the direction of the strokes of said needles, said sinkers being arranged and shaped so as to form a stitch comb capable of holding down at predetermined intervals the fabric produced by the knitting implements of the machine, a stationary trick plate having slots for the passage of said needles, and a series of spaced stationary guiding elements, one end of each of said spaced stationary guiding elements being secured to a stationary part of the machine opposite said trick plate, the other end of each of said spaced stationary guiding elements being in loose engagement with a portion of said trick plate adjacent a slot thereof, and each of said sinkers extending into a space between said spaced stationary guiding elements.

3. A warp knitting machine comprising: a needle bar carrying a series of latch needles, a needle bar drive associated with said needle bar for imparting periodic reciprocating movements to same with its latch needles in a predetermined direction, at least one guide bar carrying a series of warp guides, a guide bar drive associated with said guide bar for periodic actuations thereof with its warp guides so as to feed warp yarns to said latch needles, a sinker bar carrying a series of sinkers, a sinker bar drive associated with said sinker bar for imparting periodic movements to same with its sinkers toward and away from the direction of the strokes of said latch needles, said sinkers being arranged and shaped so as to form a stitch comb capable of holding down at predetermined intervals the fabric produced by the knitting implements of the machine, a latch retaining mechanism, said latch retaining mechanism including reciprocal members carrying a latch retaining wire extending substantially parallel to said latch needles, and a latch retainer drive associated with said latch retaining mechanism for imparting periodic movements to said latch retaining wire toward and away from the direction of the strokes of said latch needles, said latch retaining wire being arranged for being in the path of the latches of the open latch needles so as to prevent a closing thereof when the latch

retaining wire is substantially in its extreme position near the latch needles at the time of disengagement of the loops of the fabric from the latches of the open latch needles.

5 4. In a warp knitting machine as claimed in claim 3, said sinker bar drive and said latch retainer drive being coupled with each other for a substantially simultaneous movement of said sinkers and said latch retaining wire in same directions.

10 5. In a warp knitting machine as claimed in claim 3, said latch retaining mechanism including a swingable arm on each side of the machine, said latch retaining wire being stretched between 15 said swingable arms, and said latch retainer drive being associated with said swingable arms.

6. A warp knitting machine as claimed in claim 3 including a series of spaced stationary guiding elements mounted on a stationary part of the machine, each of said sinkers extending into a space between said spaced stationary guiding elements whereby said sinkers are guided by said stationary guiding elements during a movement thereof.

20 25 7. A warp knitting machine as claimed in claim 3 including a stationary trick plate having apertures for the passage of said needles, and a series of spaced stationary guiding elements, said series of spaced stationary guiding elements being secured to a stationary part of the machine and extending between said stationary part and said stationary trick plate, and each of said sinkers extending into a space between said stationary guiding elements.

30 35 8. A warp knitting machine as claimed in claim 3 including a stationary trick plate having slots for the passage of said needles, and a series of spaced stationary guiding elements, one end of each of said spaced stationary guiding elements 40 being secured to a stationary part of the machine opposite said trick plate, the other end of each of said spaced stationary guiding elements being in loose engagement with a portion of said trick plate adjacent a slot thereof, and each of said sinkers extending into a space between said spaced stationary guiding elements.

45 9. A warp knitting machine comprising: a needle bar carrying a series of needles, a needle bar drive associated with said needle bar for imparting periodic reciprocating movements to same with its needles in a predetermined direction, at least one guide bar carrying a series of warp guides, a guide bar drive associated with said guide bar for periodic actuations thereof with its warp guides so as to feed warp yarns to said needles, at least one filler thread carrier, a carrier drive associated with said filler thread carrier for imparting periodic reciprocating movements to same so as to lay filler thread substantially parallel to said series of needles, a series of spaced stationary elements arranged in such a relationship to said reciprocable filler thread carrier that filler thread laid by the latter is placed onto said series of spaced stationary elements, a sinker bar carrying a series of filler sinkers, and a sinker bar drive associated with said sinker bar for imparting periodic movements toward and away from the direction of the strokes of said needles, said filler sinkers being arranged for placing, during their movement toward said needles, the filler thread laid onto said spaced stationary elements in position to be incorporated into fabric produced by the knitting implements of the machine, and said filler sinkers and said spaced stationary elements being arranged in such a relationship to each other that

11

each of said filler sinkers extends into a space between adjacent elements and that in any position of the filler sinkers at least a portion of each filler sinker is embraced by such adjacent elements.

10. A warp knitting machine comprising: a needle bar carrying a series of needles, a needle bar drive associated with said needle bar for imparting periodic reciprocating movements to same with its needles in a predetermined direction, at least one guide bar carrying a series of warp guides, a guide bar drive associated with said guide bar for periodic actuations thereof with its warp guides so as to feed warp yarns to said needles, at least one filler thread carrier, a carrier drive associated with said filler thread carrier for imparting periodic reciprocating movements to same so as to lay filler thread substantially parallel to said series of needles, a series of spaced stationary elements arranged in such a relationship to said reciprocable filler thread carrier that filler thread laid by the latter is placed onto said series of spaced stationary elements, each of said spaced elements being engaged with a stationary part of the machine at both of its ends, a sinker bar carrying a series of filler sinkers, and a sinker bar drive associated with said sinker bar for imparting periodic movements toward and away from the direction of the strokes of said needles, said filler sinkers being arranged for placing, during their movement toward said needles, the filler thread laid onto said stationary elements in position to be incorporated into fabric produced by the knitting implements of the machine, and each of said filler sinkers extending into a space between said spaced stationary elements.

11. A warp knitting machine comprising: a needle bar carrying a series of needles, a needle bar drive associated with said needle bar for imparting periodic reciprocating movements to same with its needles in a predetermined direction, at least one guide bar carrying a series of warp guides, a guide bar drive associated with said guide bar for periodic actuations thereof with its warp guides so as to feed warp yarns to said needles, a series of spaced stationary guiding elements, at least one filler thread carrier, a carrier drive associated with said filler thread carrier for imparting periodic reciprocating movements to same so as to lay filler thread substantially parallel to said series of needles onto said series of spaced stationary guiding elements, a sinker bar carrying a series of filler sinkers, and a sinker bar drive associated with said sinker bar for imparting periodic movements toward and away from the direction of the strokes of said needles, said filler sinkers being arranged for placing, during their movement toward said needles, the filler thread laid onto said stationary guiding elements in position to be incorporated into fabric produced by the knitting implements of the machine, each of said filler sinkers extending into a space between said spaced stationary guiding elements, and the upper edge of each of said spaced stationary guiding elements being shaped for shielding the free ends of said filler sinkers when they are in their extreme retracted position away from said needles.

12. A warp knitting machine comprising: a needle bar carrying a series of needles, a needle bar drive associated with said needle bar for imparting periodic reciprocating movements to same with its needles in a predetermined direction, at least one guide bar carrying a series of warp guides, a guide bar drive associated with said guide bar for periodic actuations thereof with its warp

12

guides so as to feed warp yarns to said needles, a stationary trick plate having apertures for the passage of said needles, a series of spaced stationary guiding elements, said series of spaced stationary guiding elements being secured to a stationary part of the machine and extending between said stationary part and said stationary trick plate, at least one filler thread carrier, a carrier drive associated with said filler thread carrier for imparting periodic reciprocating movements to same so as to lay filler thread substantially parallel to said series of needles onto said series of spaced stationary guiding elements, a sinker bar carrying a series of filler sinkers, and a sinker bar drive associated with said sinker bar for imparting periodic movements toward and away from the direction of the strokes of said needles, said filler sinkers being arranged for placing, during their movement toward said needles, the filler thread laid onto said stationary guiding elements in position to be incorporated into fabric produced by the knitting implements of the machine, and each of said filler sinkers extending into a space between said spaced stationary guiding elements.

13. A warp knitting machine comprising: a needle bar carrying a series of needles, a needle bar drive associated with said needle bar for imparting periodic reciprocating movements to same with its needles in a predetermined direction, at least one guide bar carrying a series of warp guides, a guide bar drive associated with said guide bar for periodic actuations thereof with its warp guides so as to feed warp yarns to said needles, a stationary trick plate having slots for the passage of said needles, a series of spaced stationary guiding elements, one end of each of said spaced stationary guiding elements being secured to a stationary part of the machine opposite said trick plate, the other end of each of said spaced stationary guiding elements being in loose engagement with a portion of said trick plate adjacent a slot thereof, at least one filler thread carrier, a carrier drive associated with said filler thread carrier for imparting periodic reciprocating movements to same so as to lay filler thread substantially parallel to said series of needles onto said series of spaced stationary guiding elements, a sinker bar carrying a series of filler sinkers, and a sinker bar drive associated with said sinker bar for imparting periodic movements toward and away from the direction of the strokes of said needles, said filler sinkers being arranged for placing, during their movement toward said needles, the filler thread laid onto said stationary guiding elements in position to be incorporated into fabric produced by the knitting implements of the machine, and each of said filler sinkers extending into a space between said spaced stationary guiding elements.

14. A warp knitting machine comprising: a needle bar carrying a series of latch needles, a needle bar drive associated with said needle bar for imparting periodic reciprocating movements to same with its latch needles in a predetermined direction, at least one guide bar carrying a series of warp guides, a guide bar drive associated with said guide bar for periodic actuations thereof with its warp guides so as to feed warp yarns to said latch needles, at least one filler thread carrier, a carrier drive associated with said filler thread carrier for imparting periodic reciprocating movements to same so as to lay filler thread substantially parallel to said series of latch needles, a sinker bar carrying a series of filler sinkers, a

13

sinker bar drive associated with said sinker bar for imparting periodic movements to same with its filler sinkers toward and away from the direction of the strokes of said latch needles, said filler sinkers being arranged for placing, during their movement towards said latch needles, the filler thread laid by said filler thread carrier in position to be incorporated into fabric produced by the knitting implements of the machine, a latch retaining mechanism, said latch retaining mechanism including reciprocable members carrying a latch retaining wire extending substantially parallel to said latch needles, and a latch retainer drive associated with said latch retaining mechanism for imparting periodic movements to said latch retaining wire toward and away from the direction of the strokes of said latch needles, said latch retaining wire being arranged for being in the path of the latches of the open latch needles so as to prevent a closing thereof when the latch retaining wire is substantially in its extreme position near the latch needles at the time of disengagement of the loops of the fabric from the latches of the open latch needles.

15 16. In a warp knitting machine as claimed in claim 14, said sinker bar drive and said latch retainer drive being coupled with each other for a substantially simultaneous movement of said filler sinkers and said latch retaining wire in same directions.

17. In a warp knitting machine as claimed in claim 14, said latch retaining mechanism including a swingable arm on each side of the machine, said latch retaining wire being stretched between said swingable arms, and said latch retainer drive being associated with said swingable arms.

18. A warp knitting machine comprising: a needle bar carrying a series of latch needles, a needle bar drive associated with said needle bar for imparting periodic reciprocating movements to same with its latch needles in a predetermined direction, at least one guide bar carrying a series of warp guides, a guide bar drive associated with said guide bar for periodic actuations thereof with its warp guides so as to feed warp yarns to said latch needles, a series of spaced stationary guiding elements, at least one filler thread carrier, a carrier drive associated with said filler thread carrier for imparting periodic reciprocating movements to same so as to lay filler thread substantially parallel to said series of latch needles onto said series of spaced stationary guiding elements, a sinker bar carrying a series of filler sinkers, each of said filler sinkers extending into a space between said spaced stationary guiding elements, a sinker bar drive associated with said sinker bar for imparting periodic movements to same with its filler sinkers toward and away from the direction of the strokes of said latch needles, said filler sinkers being arranged for placing, during their movement towards said latch needles, the filler thread laid onto said stationary guiding elements in position to be incorporated into fabric produced by the knitting implements of the machine, a latch retaining mechanism, said latch retaining

14

mechanism including reciprocable members carrying a latch retaining wire extending substantially parallel to said latch needles, and a latch retainer drive associated with said latch retaining mechanism for imparting periodic movements to said latch retaining wire toward and away from the direction of the strokes of said latch needles, said latch retaining wire being arranged for being in the path of the latches of the open latch needles so as to prevent a closing thereof when the latch retaining wire is substantially in its extreme position near the latch needles at the time of disengagement of the loops of the fabric from the latches of the open latch needles.

19. A warp knitting machine as claimed in claim 17 including: a stationary trick plate having apertures for the passage of said latch needles, said series of spaced stationary guiding elements being secured to a stationary part of the machine and extending between said stationary part and said stationary trick plate.

20. A warp knitting machine as claimed in claim 17 including: a stationary trick plate having slots for the passage of said latch needles, one end of each of said spaced stationary guiding elements being secured to a stationary part of the machine opposite said trick plate, and the other end of each of said spaced stationary guiding elements being in loose engagement with a portion 30 of said trick plate adjacent a slot thereof.

21. In a warp knitting machine as claimed in claim 17, said sinker bar drive and said latch retainer drive being coupled with each other for a substantially simultaneous movement of said filler sinkers and said latch retaining wire in same directions.

22. In a warp knitting machine as claimed in claim 17, said sinker bar drive and said latch retainer drive being coupled with each other for a substantially simultaneous movement of said filler sinkers and said latch retaining wire in same directions.

23. In a warp knitting machine as claimed in claim 17, said sinker bar drive and said latch retainer drive being coupled with each other for a substantially simultaneous movement of said filler sinkers and said latch retaining wire in same directions.

FRITZ LAMBACH.
